UNITED STATES PATENT OFFICE

RALPH D. MERSHON, OF NEW YORK, N. Y.

ELECTROLYTIC CONDENSER

Original application filed December 31, 1925, Serial No. 78,534. Patent No. 1,773,492. Divided and this application filed January 25, 1928. Serial No. 249,314.

This invention relates to electrolytic condensers, and its chief object is to provide a compact condenser of good efficiency, which can be manufactured at low cost. To this and other ends the invention comprises the novel features and combinations hereinafter described.

While the invention can be employed in various situations the advantages above mentioned make it especially useful in radio apparatus, as for example as a "smoothing" condenser in devices for eliminating the ripple in rectified alternating current, and accordingly I have selected for illustration and specific description herein an embodiment designed particularly for the purpose named. In this form it is easily possible to construct a condenser of cylindrical shape not more than two and a fourth inches in diameter and four inches in length, having a capacity of fifty microfarads. The anode, composed of aluminum or other metal capable of forming the necessary dielectric film on its surface, may be a strip of sheet metal fastened to and wound spirally around a stiff rod of the same metal. This rod may form the anode terminal. The turns may be spaced apart in any convenient and suitable manner, to permit circulation of the electrolyte, as for example by indenting the sheet metal to form numerous lugs on one side of the same. The anode, in whatever form it is made, is immersed in a suitable electrolyte, say an aqueous solution of borax and boric acid, in a cylindrical vessel of sheet copper, which may serve as the cathode.

One embodiment of the invention is illustrated in the accompanying drawing, in which

Fig. 1 shows one end of an indented sheet metal strip before coiling.

Fig. 2 is a section on line 2—2 of Fig. 1.

Fig. 3 shows one end of the strip fastened to the rod around which it is to be coiled.

Fig. 4 is a section on line 4—4 of Fig. 3.

Fig. 5 is a side view of the complete anode.

Fig. 6 is a section on line 6—6 of Fig. 5.

Fig. 7 is a detail section, on a larger scale, on line 7 of Fig. 5.

Fig. 8 shows the complete condenser, partly in section.

The aluminum strip 10, Fig. 1, may be of any suitable thickness, 0.006 of an inch being satisfactory for a condenser of the size and capacity mentioned above. Along one edge, or both if desired, are three rows of indentations parallel to the edge, forming three rows of small lugs or bosses 11. Those in the upper and outer row are on, or protrude from, one side of the strip and those in the middle row are on the other side, as clearly shown in Fig. 2. The rest of the strip may be indented, in the same or in any other convenient "pattern", but if the lugs are elongated, as shown at 12, for example, I prefer to make them in diagonal lines, as being less apt to cause the spiral turns of the strip, in coiling it around the center stem or rod, to take polygonal cross section. I also prefer separated lugs rather than continuous ribs, as permitting freer flow of convection currents in the electrolyte. In any case the lugs or, generally, the "spacers", are preferably as sharp as possible, and in some cases it may be advantageous to make the indentations in such manner as to actually perforate the metal, producing sharp edges as indicated at 12a, Fig. 2, or 11a, Fig. 7, so that when the strip is coiled the point of contact between the apex of the lug and the adjoining turn or convolution will have a very minute area, as I have found that the smaller the area of contact the less opportunity there is for corrosion at such points.

The aluminum rod 13 is split for a portion of its length to receive the end of the strip 10, which is welded to the rod along its end edge. The strip is then coiled around the rod in spiral form, the lugs or spacers holding the turns apart to permit access of the electrolyte to all parts of the spiral anode thus formed and to allow free circulation of the electrolyte. The three parallel rows of lugs or spacers at the upper edge interlock, as it were, in the manner indicated in Fig. 7, and thus serve to limit the axial displacement of the turns. Otherwise a slight stress exerted axially might distort the device into a pro-

nounced conical form, as will be readily understood.

The container or tank for the electrolyte and anode may be a cylindrical vessel 14, Fig. 8, of suitable non-filming sheet metal. For economy of space the tank may be just large enough to receive the anode and, preferably, leave room for an insulating lining or other means to prevent electrical contact between the anode and the tank. Otherwise it may be desirable to wrap the anode with one or more turns of filming wire (not shown) to prevent expansion of the spirally wound strip. It will be understood, however, that since the film formed on the anode is non-conducting the anode may bear directly against the vessel without shorting the condenser as long as the film is in good condition. The insulating lining prevents electrical contact if the film should be worn off by friction or be otherwise impaired. A lining for the purpose indicated may consist of a bottom disk 15 of thin celluloid or cellophane and a strip 16 of like material bent to cylindrical form and placed loosely in the vessel, celluloid and cellophane being unharmed by and harmless to the electrolyte. The vessel may be closed by a disk 17 of insulating material resting on a bead 18 on the inside near the top. Around the closure at the edge is a thin flat ring or gasket of rubber or other suitable material, and the edge of the vessel is crimped or turned in and down upon this gasket, forming a seal. A vent hole 19 is provided in the cover 17. This can be plugged with wax to prevent spilling of the electrolyte in shipment and handling. When the condenser is put into service the wax can be perforated with a pin to permit escape of any gases resulting from electrolytic action in the electrolyte. Or the usual disk of thin sheet rubber can be cemented over the vent hole. When punctured with a pin the disk serves as an automatic valve, opening when the pressure of the gas rises inside the tank and closing as soon as the pressure is relieved. The tank is preferably deep enough, as in Fig. 8 for example, where the dotted line 20 indicates the surface of the electrolyte, to permit a substantial depth of electrolyte above the anode. The reserve thus provided takes care of the slow loss by electrolytic decomposition and in most cases makes it unnecessary to provide the vessel with a filling aperture and a removable closure therefor.

The rod 13, threaded on its upper end, extends through the lid 17 to form the positive terminal and is clamped to the lid by nuts 21 set up firmly on yielding gaskets 22. The negative terminal may be a screw 23 on a bracket 24 soldered to the can 14.

The electrolyte is preferably the one described in my Patent No. 1,141,402, issued June 1, 1915; compounded in the following proportions: saturated borax solution (dis-

tilled water), two gallons; boric acid, three pounds; and an additional half-pound of borax.

The necessary film can be formed on the anode in any suitable manner, as for example by the methods described in my prior Patents Nos. 1,012,889 of December 26, 1911, and 1,388,874 of August 30, 1921. Preferably the film is formed at such voltage as will permit the condenser to withstand a substantial operating voltage, say 400.

It is to be understood that the invention is not limited to the specific construction herein illustrated and described but may be embodied in other forms without departure from its spirit. The anode shown forms no part of the invention, since any suitable type of anode may be used, preferably made of sheet metal so disposed as to have a large area of contact with the electrolyte. The anode described herein is claimed in my pending application Serial No. 78,534, filed December 31, 1925, now Patent No. 1,773,492, issued August 19, 1930, of which the present application is a division.

I claim—

1. In an electrolytic condenser, a filmed metal anode, an electrolyte in which the anode is immersed, an unfilmed metal cathode surrounding the anode and in contact with the electrolyte, and a sheet of flexible non-conducting material, harmless to the electrolyte and unharmed thereby, surrounding the anode between the same and the cathode.

2. In an electrolytic condenser, an electrode comprising a strip of filmed metal bent spirally, an electrolyte in which the anode is immersed, a current-carrying member of non-filming metal surrounding the spiral anode and in contact with the electrolyte, and a flexible sheet of celluloid around the immersed spiral anode between the same and the non-filming metal member.

3. In an electrolytic condenser, a cathode of non-filming metal in the form of a containing vessel, an electrolyte therein, an anode of filming metal immersed in the electrolyte, and a lining of sheet celluloid in the vessel between the same and the immersed electrolyte.

4. In an electrolytic condenser, an anode of filming metal, an electrolyte in which the anode is immersed, a cathode of non-filming sheet metal in the form of a vessel enclosing the immersed anode, and a sheet of flexible celluloid around the anode between the same and the cathode.

In testimony whereof I hereto affix my signature.

RALPH D. MERSHON.
